UNITED STATES PATENT OFFICE.

HARRY HOUSE MORRELL, OF NEW SUFFOLK, NEW YORK.

SUBMARINE BOAT.

SPECIFICATION forming part of Letters Patent No. 726,085, dated April 21, 1903.

Application filed January 16, 1903. Serial No. 139,297. (No model.)

To all whom it may concern:

Be it known that I, HARRY HOUSE MORRELL, a citizen of the United States, and a resident of New Suffolk, in the county of Suffolk and State of New York, have invented new and useful Improvements in Submarine Boats, of which the following is a full, clear, and exact description.

The object of the invention is to provide certain new and useful improvements in submarine boats whereby a convenient means is afforded for the escape of the occupants in case the submerged boat becomes disabled and incapable of rising to the surface of the water, the said means also permitting a diver or other person to leave the boat for investigating or other purposes.

The invention consists of novel features and parts and combinations of the same, as will be more fully described hereinafter and then pointed out in the claims.

A practical embodiment of the invention is represented in the accompanying drawings, forming a part of this specification, in which similar characters of reference indicate corresponding parts in both views.

Figure 1 is a transverse section of the improvement, and Fig. 2 is a longitudinal sectional elevation of the same.

A submarine boat of any approved construction is provided within its shell A, with a chamber B preferably depending from the top of the shell and having a door C for permitting persons to pass from the chamber into the interior of the boat, or vice versa, and in the top of the chamber is arranged an escape D, preferably made tubular and extending downward a distance into the chamber to form, with the latter, an air-lock or breathing-space E in case the water flows through the escape D into the said chamber, as shown in Fig. 2. The top of the escape D opens directly into the water surrounding the boat, as shown, and the said escape is preferably concentric with the chamber B to form a ring-shaped air-lock or breathing-space to readily accommodate one or more persons, as the case may be. The escape D may be the conning-tower of the boat, and the chamber B may be either a permanent fixture of the boat or a

portable one adapted to be set up in case of need; but in every instance it is necessary that the escape D and the chamber B form an air-lock or breathing-space, so that when the chamber fills with water it drives the air contained in the chamber into the air-lock or breathing-space, so that a person or persons standing in the chamber have their heads within the breathing-space to enable them to breathe freely, and then the persons quickly diving under the escape D can pass up through the latter and to the surface of the water, thereby effecting their escape.

The escape D is provided on the top with an outwardly-opening cover F, hinged at F' and provided at its fulcrum end with a segmental worm-wheel F² in mesh with a worm G, fastened on the upper end of a shaft G', extending through a stuffing-box G² to the inside of the chamber B, and on the lower end of the said shaft is secured a bevel gear-wheel G³ in mesh at opposite sides with bevel gear-wheels H and I, secured on shafts H' and I', respectively, of which the shaft H' extends within the chamber B and is provided with a hand-wheel H² under the control of the person within the chamber B. The other shaft I' extends through a stuffing-box I² to the inside of the boat, and on the inner end of the said shaft is secured a hand-wheel I² under the control of a person within the boat, so that either a person in the chamber B or a person within the boat outside of the chamber can manipulate the cover F, so as to swing the same into an open or closed position, it being understood that when either shaft H' or I' is rotated a rotary motion is given to the worm-shaft G', which by the worm G and worm-wheel F² imparts a swinging motion to the cover F, so as to swing the same into an open or closed position, according to the direction in which the corresponding hand-wheel H² or I² is turned.

Into the upper end of the air-lock or breathing-space E opens an air-supply pipe J, connected with a suitable source of compressed-air supply, and in the said pipe J is arranged an inlet-valve K and an air-discharge valve L, of which the latter opens into the boat, as plainly indicated in Fig. 1. The stems K' and

L' of the valves K and L are each provided with two handles, one inside the chamber B and one outside thereof, within the boat, so that the valves K and L can be manipulated 5 either from within the chamber B or within the boat.

From the bottom of the chamber B leads an outlet-pipe N for carrying off water, and the said pipe is provided with a valve N', 10 having its valve-stem N² extending through a stuffing-box N³ to pass within the chamber B, and on the said stem N² are secured hand-wheels N⁴ and N⁵, of which the latter is located inside of the chamber B and the other 15 outside thereof, within the boat. Thus the valve N' can be opened or closed either from within the chamber B or from within the boat.

Now when the cover F is closed and it is desired to discharge the water in the chamber B then the valve N' is opened and air-pressure is let into the air-lock or space E by way of the pipe J, so as to drive the water out of the said chamber to empty the same, the water passing by way of the pipe N to a 25 tank or other suitable place of discharge. If desired, the pipe N may be connected with a pipe O, having a valve O' and leading to a pump to pump the water out of the chamber B when the cover F is closed and air-pressure 30 is not available. The water may also be drained out of the chamber B by connecting the pipe N with a drain-pipe P, leading to a suitable place of discharge within the submarine boat.

35 The operation is as follows: When the cover F is closed and the submarine boat becomes disabled while submerged and not capable of rising to the surface and the occupants of the boat desire to escape, then one of the occupants passes through the door C into the chamber B, then closes the said door C and swings the cover F open, so that the water surrounding the boat flows through the escape D into the chamber B to form an air-lock or breathing-space E, as previously described, for the person in the chamber B to breathe in. This person now dives under, as previously described, and passes through the escape D to the surface of the water, and then a second 45 person within the boat manipulates the hand-wheel I', so as to close the cover F, and then manipulates the necessary devices described for discharging the water from the chamber B. When this has been done and the chamber B is again emptied of the water previously 50 admitted, then the door C is opened and the second person passes into the chamber B, then closes the door C and repeats the above-described operation—that is, first opens the cover F to allow water to pass into the chamber to form the air-lock or breathing-space, then escapes through the escape D to the surface of the water. This operation is successively repeated by all the occupants of 55 the boat, so that each one can readily effect

an escape. It will be also seen that the arrangement described affords a convenient means for a diver to leave the submerged boat for investigating or other purposes.

The chamber B is provided at the air-lock 70 portion E with a window Q to enable persons within the boat to see when a person has escaped from the chamber B.

Having thus described my invention, I claim as new and desire to secure by Letters 75 Patent—

1. A submarine boat having an escape opening directly into the water when the boat is submerged, and local means in the boat for receiving the water passing through the 80 escape, the said means serving to retain the water and thereby form a breathing-space adjacent to the escape, as set forth.

2. A submarine boat having a chamber within the boat and provided with a tubular 85 escape extending into the chamber, to form with the latter an air-lock or breathing-space when the chamber fills with water, the top of the escape opening directly into the water surrounding the boat, as set forth.

3. A submarine boat having a chamber within the boat and provided with means for establishing connection between the chamber and the interior of the boat, and an escape extending downwardly into the chamber, to form with the latter an air-lock or breathing-space at the time the chamber fills with water through the said escape, as set forth.

4. A submarine boat having a chamber 100 within the boat and provided with a tubular escape extending into the chamber, to form with the latter an air-lock or breathing-space when the chamber fills with water, the top of the escape opening directly into the water 105 surrounding the boat, and a door leading from the chamber into the interior of the boat, as set forth.

5. A submarine boat having a chamber within the boat and provided with a tubular 110 escape extending into the chamber, to form with the latter an air-lock or breathing-space when the chamber fills with water, the top of the escape opening directly into the water 115 surrounding the boat, a cover for the said escape, and mechanism for operating the cover to move the same into an open or closed position from within the chamber, as set forth.

6. A submarine boat having a chamber within the boat and provided with a tubular 120 escape extending into the chamber, to form with the latter an air-lock or breathing-space when the chamber fills with water, the top of the escape opening directly into the water 125 surrounding the boat, and an air-supply for the said air-lock or breathing-space, as set forth.

7. A submarine boat having a chamber within the boat and provided with a tubular escape extending into the chamber, to form 130

with the latter an air-lock or breathing-space when the chamber fills with water, the top of the escape opening directly into the water surrounding the boat, a cover for the said escape, mechanism for opening or closing the said cover, and means for discharging the water from the said chamber, as set forth.

In testimony whereof I have signed my name to this specification in the presence of two subscribing witnesses.

HARRY HOUSE MORRELL.
